UNITED STATES PATENT OFFICE.

LATHAM H. BRIGHTMAN, OF COLUMBUS, OHIO.

FEED DEVICE FOR NUT-MACHINES.

1,246,863.

Specification of Letters Patent.

Patented Nov. 20, 1917.

Application filed September 20, 1915. Serial No. 51,564.

To all whom it may concern:

Be it known that I, LATHAM H. BRIGHTMAN, a citizen of the United States, residing at Columbus, in the county of Franklin 5 and State of Ohio, have invented certain new and useful Improvements in Feed Devices for Nut-Machines, of which the following is a specification.

The present invention is associated with 10 the art of making nuts, and has particular bearing to machines for feeding the stock bar into the nut making machine. My invention is particularly applicable to those types of machines in which the nuts are 15 made from the stock in its cold condition as opposed to hot pressed nuts.

The main object of my invention resides 20 in the provision of a structure for gripping the stock bar in such manner that no score 25 marks of any kind are left on the same to mar the appearance of the nuts and to further grip this stock bar in a positive manner so that play is impossible.

A further object of my invention resides 25 in the provision of an eccentrically mounted gripping wheel structure, the gripping wheel being so constructed that its larger portion or crest is caused to move into gripping or holding contact with the stock bar 30 faces.

A further object of my invention resides 35 in a spring structure for normally governing the gripping wheel so that the stock bar is gripped to prevent movement in one direction and is free to move in the other direction. In this connection, my invention also has for its object the provision of adjusting means for varying the tension of 40 this spring structure.

The preferred embodiment of my invention is shown in the accompanying sheet of drawings, in which similar characters of reference designate corresponding parts, and 45 in which:

Figure 1 is a view in side elevation of my feed mechanism, and,

Fig. 2 is a front elevation of the structure shown in Fig. 1, looking from the right of the sheet, a portion of which is also shown 50 in section.

In these drawings, the supporting framework is designated generally by the reference numeral 1, and comprises a pair of sleeves 2 slidably mounted upon guide rails 3. This supporting framework is further 55 provided with a cap 4 and is formed to

rotatably receive a feed head 5. This feed head is formed with a longitudinally extending hollowed out portion 6, through which the stock bar is adapted to pass and is 60 prevented from longitudinal movement within the framework by means of the shoulders presented at 7 and 8. The forward end of this feed head is shaped to present side pieces 9 to support bearings 10 65 and 11 at its upper and lower ends respectively. All of these bearing portions are bored to receive bushings 11^a and these bushings are in turn bored to rotatably receive the spindles 12. Upon each of these 70 spindles there is mounted a gripping wheel such as is shown at 13 and an inspection of Fig. 1 will show that each of these gripping wheels is eccentrically mounted on its respective spindle in the sense that its center 75 of rotation is not in the center of the wheel. I have also provided spring means for normally tending to rotate these gripping wheels so that their larger portions will lie 80 opposite each other and this spring means is shown in the form of a plurality of torsion springs 14, one end of each spring being fastened in its respective bushing as is shown at 15 and the opposite end of each being secured in a transverse hole 17 in the 85 corresponding gripping wheel. These gripping wheels are preferably made with a V-face so that each wheel will engage two faces 90 of the stock bar, it being, of course, understood that these gripping wheels are constructed to fit the particular type of bar to which they are applicable. Further, I wish it understood that the particular shape of the gripping wheel faces is not of vital importance. Each of the gripping wheels is 95 also provided with a series of radially arranged holes 18 into which a suitable tool may be inserted to turn them to permit the insertion of a piece of stock and immediately upon their release, the springs 14 act 100 to bring them into wedging engagement with the stock bar faces. In order to regulate the tension of these torsion springs, the opposite sides of the protruding ends of each of the bushings 11 are flattened as is shown 105 at 19 and, therefore, by the application of a wrench, these bushings may be rotated to increase or decrease the tension of the springs as desired and the bushings then in turn held permanently in position by tightening of the set screws 20.

The manner of operating my device is as

follows: The gripping wheels 13 are turned in a direction to present the maximum distance between their faces and this gripping may be effected by hand or by the use of 5 suitable tools inserted in the radially arranged holes 18. After the stock bar is in position between the gripping wheels, these wheels are released and the tension of the springs 14 is such as to cause their rotation 10 to move the larger portions of the wheels into engagement with the stock bar faces. As shown in Fig. 1, movement of the entire framework toward the right, which may be effected by a pull upon the link 21, pivoted 15 to the general framework as shown at 22, will cause a movement of the entire stock bar in a forward direction since any rotative tendency of the gripping wheels will only move them into firmer engagement with the 20 stock bar. Return movement or movement toward the left of the general framework is possible, however, since movement in this direction has a tendency to unwind the spring 14 and consequently to release the 25 wedging effect between the gripping wheels and the stock bar. Then, because of the rotative connection between the feed head 5 and the supporting framework, this stock bar may be continually rotated and consequently the machine to which the feeding 30 mechanism is applied, need not be stopped in order to give a feed sufficient for the formation of additional nuts.

From the foregoing description, it will be 35 apparent that I have provided a type of gripping means wherein all score marks impressed in the stock bar faces is eliminated and at the same time a positive grip is attained. Further, by means of these eccentrically mounted wheels, bars varying in size 40 may also be operated upon.

What I claim, is:

1. A feed device of the character described comprising a feed head rotatably mounted 45 to rotate with the stock bar as a center and supported to be capable of longitudinal re-

ciprocatory movement, a pair of eccentrically mounted wheels carried by said head between which the stock bar is adapted to pass so that longitudinal movement of the 50 head in one direction will wedge the stock bar between said rollers, means acting in conjunction with said wheels for normally urging their larger portions toward the stock bar, and means coöperating with and 55 arranged to vary the tension of said last named means.

2. A feed device of the character described comprising a feed head rotatably mounted to rotate continuously in the same direction with the stock bar as a center and supported to be capable of longitudinal reciprocal movement, a pair of eccentrically mounted wheels carried by said head between which the stock bar is adapted to 60 pass so that longitudinal movement of the head in one direction will wedge the stock bar between said rollers, torsion springs coöperating with said wheels in a manner to normally urge the larger portions of said 65 wheels toward the stock bar, a means whereby the tension of said springs may be varied.

3. A feed device of the character described comprising a feed head rotatably mounted 75 to rotate with the stock bar as a center and supported to be capable of longitudinal reciprocal movement, a pair of transverse spindles in said head, an eccentrically bored gripping wheel for each spindle, a bushing 80 in which one end of each spindle is mounted, a torsion spring encircling each spindle and engaging its respective wheel at one end and bushing at its other end, and means whereby said bushing may be held in any position 85 of rotative adjustment.

In testimony whereof I affix my signature in presence of two witnesses.

LATHAM H. BRIGHTMAN.
